J. BLOOM

BADGE

Filed May 31, 1927

INVENTOR.

Joseph Bloom

BY

John Flan
ATTORNEY.

UNITED STATES PATENT OFFICE.

JOSEPH BLOOM, OF LOS ANGELES, CALIFORNIA.

DESIGN FOR A BADGE.

Application filed May 31, 1927. Serial No. 22,227. Term of patent 14 years.

To all whom it may concern:

Be it known that I, JOSEPH BLOOM, a citizen of the United States, and a resident of the city of Los Angeles, State of California, have invented a new, original, and ornamental Design for a Badge, of which the following is a specification, reference being has to the accompanying drawings, forming part thereof.

I claim:

The ornamental design for a badge substantially as shown.

JOSEPH BLOOM.
